(57) **CLAIM**

The ornamental design for a guitar neck and head, as shown and described.

DESCRIPTION

FIG. 1 is a top view of a guitar neck and head showing my new design;

FIG. 2 is a bottom view of the guitar neck and head of FIG. 1;

FIG. 3 is a left side view of the guitar neck and head of FIG. 1;

FIG. 4 is a right side view of the guitar neck and head of FIG. 1;

FIG. 5 is a perspective view of the guitar neck and head of FIG. 1;

FIG. 6 is a front view of the guitar neck and head of FIG. 1; and,

FIG. 7 is a rear view of the guitar neck and head of FIG. 1. Broken lines in the drawings are for the purposes of illustrating environmental structure and form no part of the claimed design.
